UNITED STATES PATENT OFFICE.

JAMES H. REDFIELD, OF SALEM, INDIANA.

MIDDLELINGS-PURIFIER.

SPECIFICATION forming part of Letters Patent No. 234,688, dated November 23, 1880.

Application filed July 1, 1880. (No model.)

To all whom it may concern:

Be it known that I, JAMES H. REDFIELD, a citizen of the United States, residing at Salem, in the county of Washington and State 5 of Indiana, have invented certain new and useful Improvements in Middlelings-Purifiers, of which the following is a specification.

My invention relates specially to middlelings-purifiers which provide for the introduction of 10 two currents or streams of air into the middlelings-purifying chamber, one stream passing in above the sieve and the other below and up through the sieve, such purifiers being also provided with a spout for conducting the middlelings up to and through the supply-passage, and a fan for elevating the middlelings and producing the two currents or streams of air introduced amid the middlelings in the purifying-chamber. The invention, however, is applicable to purifiers which do not have the 15 middlelings introduced into them from a suction-spout, but spouted directly in at the top in an approved manner now in use; and the objects and nature of my improvements will be 20 fully understood from the following specification and accompanying drawings, in which—

Figure 1 is a vertical longitudinal section of a combined middlelings elevator and purifier, having a middlelings-conducting spout, a suction-fan, and air-entrance passages above and below the sieve, as shown in Letters Patent granted to me on April 15, 1879, and also having my present improvements applied to it. Fig. 2 is a horizontal section of the machine 25 shown in Fig. 1. Fig. 3 is a partial horizontal section of the machine shown in Fig. 1, the section being taken on a lower plane than Fig. 2. Fig. 4 is a vertical transverse section of the machine. Fig. 5 is an end elevation of the 30 machine, looking at the supply or feeding end. Fig. 6 is a detail section of the hanger and support of the sieve.

Similar letters of reference in the several figures indicate corresponding parts.

45 A represents the suction-spout through which the middlelings are elevated from a floor below, or the same floor upon which the purifier is situated, and discharged into the purifying-chamber B of the purifier.

50 C is the spreading-board, which diffuses and deflects the middlelings down upon the sieve D.

E and F are air inlets or passages, the one E being above the sieve, and that F below the slatted bottom D' of the sieve-frame D². The passage E receives into it the upper end of the 55 suction-spout, and the passage F is provided with a wind-regulating slide, F'.

G is an opening into a chamber, G', on top of purifier, and in communication with the suction-fan H. The chamber G' is provided 60 with arresting-strips a, whereby light impurities passing up with the air are trapped into the chamber, while the air has freedom to pass to the fan-case H'. G² is also an air-passage leading from the purifier into the fan-case. 65

I are passages for air between the lapping edges of the slatted bottom of the frame of the sieve. J are wind-breakers arranged across the sieve, one just in rear of each of the passages I, so that the air which enters a passage 70 forward of a wind-breaker, J, will be arrested by the wind-breaker forward of said passage. Thus the air introduced into the tight chamber B' of the purifier through the passage F is divided up and thrown against the sieve-cloth 75 and forced through its meshes in such a manner that impurities above the sieve will be held up and carried over the end of the sieve into the chute-discharging receptacle K.

L is a longitudinal central partition on the 80 bottom of the sieve-frame for dividing up the surface upon which the purified middlelings fall into numerous chambers or sections, and also dividing the wind-currents longitudinally.

M is a trough placed centrally beneath the 85 slatted bottom of the sieve-frame. This trough is narrower than said bottom, and is of a length sufficient to catch the purified middlelings and the tailings. At its discharging end it is divided horizontally into two channels, b, connects with a middlelings-discharge chute, K', while the upper channel, b', connects with the return-middlelings-discharge chute K². In the partition forming the two channels of the trough M an 90 oblong opening, c, is provided, and over this opening a cut-off slide, N, is fitted, said slide having a knob, d, on its front end, by which it can be moved back and forward, and it also having an opening, c', through its middle, but 95 of less length than the opening c. Through the slats of the bottom of the sieve-frame open- 100

ings c^2 are formed on each side of the partition L, and by means of these openings the purified middlings and the return middlings are discharged into the respective channels 5 of the trough, and thence into the discharging chute-receptacles K' K². Any required number of the slats may be provided with openings c^2 .

The slide N is operated through the air- 10 passage F, and by moving this slide toward the spout K' the cut-off of the purified middlings is lengthened, and by moving it in an opposite direction the cut-off is shortened. Thus more or less purified middlings are permitted 15 to pass into the lower channel of the spout, or more or less middlings which are to be returned into the suction-spout, and thence back into the purifier for a second action upon them of the blast and sieve, are allowed to 20 pass into the upper channel of said spout, and thence into the chute discharging-receptacle K². The slats forming the bottom of the sieve-frame are inclined downward from the respective sides of said frame, and form an inverted 25 ridge directly over the trough, and thus the middlings flow laterally toward the center of the spout and then escape into the spout. By this construction the middlings are allowed to be spread by the board C over the 30 entire width of the sieve-cloth, and yet can be discharged through the central trough.

The sieve-frame is provided with a lateral extension, d, of cotton or other flexible material, and by this extension it is tacked to the 35 side walls of the purifying-chamber; and it is also provided with an end extension of the same material by which it is tacked to the feeding end of the purifier, as shown. The flexible extensions are left quite full or loose, in 40 order that the sieve-frame shall have freedom to vibrate in any manner required. These extensions form a partition or diaphragm for preventing the middlings passing downward outside the frame, and air from passing upward 45 except through the sieve-cloth.

The sieve-frame is supported and suspended by means of hanger-straps P and inclined ratchet-toothed brackets P'. The straps are provided with knife-edge bearings f, which are 50 set in any one of the V-notches between the teeth of the brackets. By this construction of the hangers and brackets great facility for adjusting the sieve-frame more or less inclined, for the purpose of having the middlings travel 55 either fast or slow over the sieve-cloth, are afforded.

The sashes D, containing the sieve-cloth, are made to slide in and outward endwise upon the frame D²; and by this construction it is 60 not necessary to remove the sieve-frame from the purifier when it is desired to clean the sieve-cloth or repair the same.

Each of the chute discharging-receptacles K K' K² is provided, as usual, with a self-opening and self-closing valve, g, and the return-middling chute K² may have a conducting-

spout, O, leading back into the suction and conducting spout A, as shown.

The fan-shaft Q is, as usual, provided with an eccentric, q, which acts as a knocker for 70 acting upon the spring-bumper r of said frame. The spring k of the bumper is placed loosely upon an angular bearing-plate, l, and its ends bear against angular slotted plates m, which are confined to the purifier-frame by set-screws 75 n. By this arrangement of the spring, as the eccentric wears away, the slack can be taken up, and the spring thus kept at a uniform tension, and improper jars and noise thus prevented. It is only necessary to loosen the set-screws, adjust the plates m and again tighten the said screws to accomplish the tension upon the spring. When a clamp, as ordinarily, is used around the eccentric, a very little wear 80 enables the eccentric to play backward and forward, and produce noise and jar; and if this clamp should be too tight it will cause heat and endanger the mill by fire.

A pulley on the fan-shaft is provided, as usual, for driving the purifier. 90

One of the leading difficulties experienced with purifiers of middlings is that of the sieve-cloth becoming clogged with the light substances which float in the atmosphere beneath the cloth, these substances being sucked up 95 against the cloth, and by accumulating finally stop all the meshes thereof and cause the middlings to run over the tail end of the sieve-frame, or, at least, interfere seriously with the air acting perfectly upon the middlings which 100 are passing over the cloth. By my improvement—to wit, the construction of the bottom of the sieve-frame of broad slats set slightly above one another, and made to overlap, as 105 shown, and in connection with this construction providing wind-breakers in front of each broad and shallow wind-passage of the bottom of the sieve-frame—the difficulty is overcome, for the strong current of air striking the wind-breakers will be directed with a whirling motion against every part of the sieve-cloth, and 110 will blow off the light substances and keep the under side of the cloth clean; and, in addition to this operation, the strong wind-currents introduced above and below the sieve-cloth will hold up the tailings until they are 115 carried over at the discharge end of the machine, and all light substances, dust, "fluff," and other impurities, will be carried into the trap or chamber G' on top of the purifier, from whence they may be removed through a door, or by lifting off the cap of the chamber. 120

The spreading-board is located just above the receiving end of the sieve-frame, and diagonally opposite the air and middlings inlet 125 passage E. It is curved in form, and extends across the sieve-frame. By this construction the middlings are uniformly spread over the sieve as well as directed downward upon its receiving end.

In some middlings-purifiers, where the suction-spout is not required or used, a tin tube, 130

say two inches in diameter, may connect with a forwardly-extended hopper on top of the machine, and the middlings may be spouted into the purifier at the feeding or front end. Underneath this tube, and flexibly connected to the frames of the sieve and purifier, a transverse board, with its back edge slightly turned up or lipped, is placed, and the middlings, by piling up on this board, gradually flow over its edge upon the sieve in a somewhat spread or diffused state. I contemplate applying my improvements in connection with such feeding devices of purifiers, and therefore do not limit myself to the suction-spout for elevating the middlings.

What I claim as my invention, and desire to secure by Letters Patent, is—

1. The combination of the slatted perforated bottom of the sieve-frame, central trough provided with two channels, $b b'$, and a sliding cut-off device, N , substantially as and for the purpose described.

2. The combination of the endwise-removable sashes of the sieve-cloth and the sieve-frame attached to the frame of the purifier

by a flexible diaphragm firmly fastened to said frame, substantially as and for the purpose described.

3. The combination of the sieve-frame, hanger-straps having knife-edge bearings, and the inclined toothed-brackets, substantially as and for the purpose described.

4. The bumper-spring k of the purifier, in combination with the plate l , slotted plates m , set-screws n , eccentric q , and bumper r of the sieve-frame, substantially as and for the purpose described.

5. The combination of the sieve having a frame formed of slats at its bottom, and provided with a central trough and transverse partitions or wind-breakers, with a casing provided with air-inlets above and below the sieve, and with a suction and conducting spout and a suction-fan, substantially as and for the purpose described.
